UNITED STATES PATENT OFFICE.

JOSEPH T. TILLMAN, OF MINNEAPOLIS, MINNESOTA.

FENCE-STAY-WIRE-FORMING MACHINE.

1,258,271.

Specification of Letters Patent. Patented Mar. 5, 1918.

Application filed September 25, 1916. Serial No. 121,997.

To all whom it may concern:

Be it known that I, JOSEPH T. TILLMAN, a citizen of the United States, residing at Minneapolis, in the county of Hennepin and 5 State of Minnesota, have invented a new and useful Improvement in Fence-Stay-Wire-Forming Machines, of which the following is a specification.

This invention relates to certain new and 10 useful improvements in wire forming machines, and more particularly contemplates the provision of an efficient machine of this character adapted to form stays or supports useful as a means for strengthening fences 15 and the like.

An object of the invention is to provide a device of this type whereby a fence stay may be formed from a single piece of spring or other wire in a simple and rapid manner, 20 the finished article being of an even, neat appearance as well as strong and durable.

Another object is to provide means whereby stays of different lengths may be formed in the same machine.

25 A still further object is to provide means whereby, upon completion of the formation of the stay, the forming parts of the machine are automatically returned to initial position for the repetition of the operation.

30 Other and further objects and advantages of the invention will be hereinafter set forth and the novel features thereof defined by the appended claims.

In the drawings:

35 Figure 1 is a side elevation, partly in section, of the machine; Fig. 2 is a plan partly in section and broken away; Fig. 3 is an end elevation; Fig. 4 is a section taken on the line X—X of Fig. 1; Fig. 5 is a section 40 broken away on the line Y—Y of Fig. 2; Fig. 6 is a detail of the clutch employed; Fig. 7 is a detail in perspective of the wire engaging block; Fig. 8 is a view broken away of the wire forming tube showing the 45 engaging block in position thereon, a wire likewise being illustrated in the process of formation; Fig. 9 shows the completed wire fence stay; and Fig. 10 is a perspective of the trip device.

50 Like characters of reference refer to like parts in the several figures of the drawings.

In the drawings, the reference character

A represents a base or platform, which as shown, is rectangular in shape, at or adjacent 55 one end of which is fixedly placed a vertically disposed housing or skeleton cas-

ing B while adjacent the opposite end is secured a standard C. Extending longitudinally and horizontally between said standard and housing near their upper extremities 60 is a rotatable hollow tube 5 having a suitable bearing 6 within the housing into which the tube projects. At equal elevations above the base A, the standard and housing are also provided with bearings 8 and 9, respectively, within which is journaled a lead screw 10 provided with continuous threads 11 of suitable pitch, an end of this lead screw extending beyond the bearing 9 into the housing and having keyed or otherwise secured thereto a gear wheel 12, a similar gear wheel 13 being secured to the corresponding end of the tube 5. A shaft 14 is journaled within the housing so as to extend transversely intermediate the gear wheels 12 and 13, said shaft being provided with a worm 15 meshing with the said gear wheels so as to rotate the same and the attached tube and lead screw as will be understood. One end of the transverse shaft 14 projects beyond its bearing in the housing and carries a pinion 16 meshing with a large gear wheel 17 secured to one extremity of a second transverse shaft 18 journaled in the housing, a suitable crank arm 19 being attached to the other end of shaft 18 for imparting rotary movement thereto. It is to be understood that the tube 5 and lead screw 10 are disposed parallel in the same vertical plane so as to afford guides upon which a follower D, to be later explained in detail, is free to move longitudinally of the base.

The follower D comprises an elongated casting having spaced enlarged portions 20 and 21 through which passages are provided, 95 a tubular forming tool 22 being rigidly attached within the passage of the enlargement 20 and affording a bearing through which the tube 5 is free to rotate and slide. The tool 22 has an integral offset hook-shaped portion 23, the purpose of which will subsequently appear.

At its enlarged portion 21, the follower is provided with a lug 24 to which is pivoted one end of a lever 25 shown as extending 105 across the lead screw 10 and as having a depending pin 26 formed with a reduced end 27 attached to the lever for oscillatory movement and in position to engage the threads 11 of the lead screw. The enlarged portion 110 21 has formed therein a passage 21' within which is reciprocably disposed a plunger 28

having a rounded end designed to engage either the upper or lower side of a finger 29 projecting from the lever, the finger being designed to ride over the rounded end of the 5 plunger, when the lever is tripped in a manner to be set forth, and thus hold the pin in or out of engagement with the lead screw.

The passage 21' is partially chambered 10 to accommodate a spring 30 bearing at one end against a collar 31 carried by the plunger and at the other end against a screw plug 32 threaded into the aperture whereby the plunger is normally maintained in outer- 15 most position.

Extending freely through an opening formed in the follower D and secured at its opposite end to the housing B and standard C intermediate the hollow tube 5 and lead screw 10 is a graduated rod 33 upon which is slidably disposed the collar 34 of a trip device E (see Fig. 10) having an integral depending plate 35 projecting therefrom provided with forks 36 and 37 at its free 20 end straddling the lead screw 10, the fork 36 being bent at an angle to the plane in which the plate 35 lies to form a trip arm against which the lever 25 impinges and by which it is raised during the operation of 25 the device to release the pin 26 from engagement with the thread 11 of the lead screw. A set-screw 38 with which the collar 34 is provided serves as a means for retaining the trip device in selected position 30 upon the graduated rod 33.

Secured upon the base A, is a longitudinally extending track 39 upon which the lower end of the follower D is adapted to ride, a spaced roller 40 journaled to the 40 follower being employed for the purpose of reducing to a minimum the friction resulting from the movement of the follower along the track. When it is desired to form a stay for fences and the like, the end of a 45 suitable wire is inserted into the end of the tube 5 remote from the gear wheel 13 until it contacts with an obstruction such as the extremity of a suitable bar 41 inserted into the other end of the tube 5 through a wall 50 of the housing where it is held by threaded engagement as shown at 42. The wire is then bent about the end of the tube from which it projects and where it is engaged by a retaining hook 43 forming an integral 55 part of the tube 5. The projecting strand of wire is likewise engaged by the hook 23 of the tool. Rotary motion is then imparted to the tube 5 and the lead screw 10 through the medium of the crank handle, enlarged 60 gear, pinion, worm and worm gears above described, the pin 26 depending from the lever 25 engaging the thread 11 of the lead screw and causing the follower D to move longitudinally and to spirally wind the wire 65 around the rotating tube 5 due to the en-

gagement, and the retention of the wire as aforesaid by the revolving hook 43 and the longitudinally moving hook 23 carried by the follower. It will be understood that the trip device has been previously positioned on the graduated rod 33 to determine the length of the stay to be formed. When the follower reaches, or approximately so, the position of the trip device, the lever 25 contacts with and is raised, during further movement of the follower, by the cam or angle surface of the fork 36 which causes the finger 29 of the lever to ride over the end of the spring pressed plunger and to lift the pin 26 from engagement with the 70 thread of the lead screw so as to automatically stop the forward movement of the follower and consequently the spiral winding of the wire on the tube 5. As soon as the pin 26 is disengaged from the thread, the 75 follower is returned to its initial or starting point under the action of a spring drum 44 carried by a bracket 45 mounted on the base as shown in Fig. 1, a cable 46 wound upon the drum and having its end connected 80 to the follower as at 47 being utilized for the purpose.

In order to cushion the return movement of the follower, a cylindrical casing 48 formed in or secured to the standard C is provided, 95 the end of said casing adjacent the follower being open and bell-shaped as shown at 49 and its other end being provided with an aperture 50 forming an air inlet adapted to be opened and closed by means of a check 100 valve 51 pivotally carried within the casing. A piston 52 having its valve stem 53 secured to the lower portion of the follower is adapted to be received within the casing through the bell-shaped open end thereof. The operation of these parts is similar to that of a number of the well known pneumatic door checks now on the market and need not therefore be explained.

As shown in Fig. 9, the completed stay 110 generally comprises a straight or core portion 54 and the convoluted portion 55, which portions are formed of a single piece of wire to increase the strength and durability of the stay. The length of the core 54 is 115 determined and regulated by the extent to which the rod 41 is inserted into the tube 5; while the length assumed by the convoluted portion 55 is regulated by the adjustment of the trip device E upon the graduated rod 33, 120 the pitch of the threads 11 on the lead screw determining the distance measured on a line parallel to the axis, between two adjacent portions of the spiral. It is to be understood that the invention contemplates the use of 125 a plurality of lead screws having threads of different pitches.

In accordance with the patent statutes, I have described the principles of operation of my invention, together with the appa- 130

ratus which I now consider to represent the best embodiment thereof, but I desire to have it understood that the construction shown is only illustrative, and that the invention can be carried out by other means and applied to uses other than those above set forth within the scope of the following claims.

Having described my invention, what I claim as new and desire to protect by Letters Patent is:

1. A fence-stay forming machine, comprising a base, a vertically extending gear casing mounted upon said base at one end thereof, a member mounted upon said base for movement to and from said gear casing, a hollow tube having a bearing adjacent one end in said casing and being provided with wire-engaging means at its other end, a forming tool having wire-engaging means secured to said member and providing a slide-bearing for said tube, a lead screw journaled in said casing and having a slide-bearing in said member, means for operably connecting said member to said lead screw, and gear mechanism within said casing for imparting simultaneous rotary movement to said rod and to said lead screw whereby said member is moved longitudinally upon said base.

2. A fence stay forming machine, comprising a base having a longitudinal track upon its face, a vertically extending gear casing mounted upon said base at one end thereof, a member mounted upon said track for movement to and from said gear casing, a hollow tube having a bearing adjacent one end in said casing and being provided with wire engaging means at its other end, a tubular forming tool having wire engaging means secured to said member and providing a slide-bearing for said tube, a lead screw journaled in said casing and having a slide-bearing in said member, means for operably connecting said member to said lead screw, and gear mechanism within said casing for imparting simultaneous rotary movement to said rod and to said lead screw whereby said member is moved upon said track.

3. A fence stay forming machine, comprising a base, a vertically extending gear casing mounted upon said base at one end thereof, a member mounted upon the base for movement to and from said gear casing, a hollow tube having a bearing adjacent one end in said gear casing and being provided with wire-engaging means at its other end, a tubular forming tool having wire-engaging means secured to said member and providing a slide-bearing for said tube, a lead screw journaled in said casing having a slide-bearing in said member, releasable means for operably connecting said member to said lead screw, and gear

mechanism within said casing for imparting simultaneous rotary movement to said rod and to said lead screw whereby said member is moved longitudinally upon said base.

4. A fence stay forming machine, comprising a base, a vertically extending gear casing mounted upon said base at one end thereof, a member mounted upon the base for movement to and from said gear casing, a hollow tube having a bearing adjacent one end in said gear casing and being provided with wire-engaging means at its other end, a tubular forming tool having wire-engaging means secured to said member and providing a slide-bearing for said tube, a lead screw journaled in said casing having a slide-bearing in said member, releasable means for operably connecting said member to said lead screw, a trip device adapted to contact with and disconnect said member from engagement with said lead screw, and gear mechanism within said casing for imparting simultaneous rotary movement to said rod and to said lead screw whereby said member is moved longitudinally upon said base.

5. A fence-stay forming machine, comprising a base, a vertically extending gear casing mounted upon said base at one end thereof, a member mounted upon the base for movement to and from said gear casing, said member having an aperture therethrough, a hollow tube having a bearing adjacent one end in said gear casing and being provided with wire-engaging means at its other end, a tubular forming tool having wire-engaging means secured to said member and providing a slide-bearing for said tube, a lead screw journaled in said casing having a slide-bearing in said member, releasable means for operably connecting said member to said lead screw, a graduated bar secured at one end to said casing and projecting through the aperture in said member, a trip device adjustably carried upon said graduated bar adapted to contact with and disconnect said member from engagement with said lead screw, and gear mechanism within said casing for imparting simultaneous rotary movement to said rod and to said lead screw whereby said member is moved longitudinally upon said base.

6. A fence-stay forming machine, comprising a base, a vertically extending gear casing mounted upon said base at one end thereof, a standard carried by said base adjacent its other end, a member mounted on said base for movement between said casing and said standard, a hollow tube having a bearing adjacent one end in said casing and being provided with wire-engaging means at its other end, a forming tool having wire-engaging means secured to said member and providing a slide-bearing for said tube, a

lead screw journaled in said casing and said standard and having a slide-bearing in said member, means for operably connecting said member to said lead screw, and gear mechanism within said casing for imparting simultaneous rotary movement to said rod and to said lead screw whereby said member is moved longitudinally upon said base.

7. A fence-stay forming machine, comprising a base, a vertically extending gear casing mounted upon said base at one end thereof, a standard carried by said base adjacent its other end, a member mounted on said base for movement between said casing and said standard, a hollow tube having a bearing adjacent one end in said gear casing and being provided with wire-engaging means at its other end, a tubular forming tool having wire-engaging means secured to 20 said member and providing a slide-bearing for said tube, a lead screw journaled in said casing and said standard and having a slide-bearing in said member, releasable means for operably connecting said member to said 25 lead screw, a graduated bar secured at one end to said casing and projecting through the aperture in said member, a trip device adjustably carried by said graduated bar adapted to contact with and disconnect said 30 releasable means from engagement with said lead screw, and gear mechanism within said casing for imparting simultaneous rotary movement to said rod and to said lead screw whereby said member is moved longitudinally upon said base.

8. A fence-stay forming machine, comprising a base, a vertically extending gear casing mounted upon said base at one end thereof, a member mounted on said base for 40 movement to and from said gear casing, a hollow tube having a bearing adjacent one end in said casing and being provided with wire-engaging means at its other end, a forming tool having wire-engaging means 45 secured to said member and providing a slide-bearing for said tube, a lead screw journaled in said casing and having a slide-bearing in said member, means pivotally carried by said member adapted to releasably engage said lead screw for imparting 50 movement to said member, a trip device adapted to contact with and disconnect said pivoted means from engagement with said lead screw, and gear mechanism within said 55 casing for imparting simultaneous rotary movement to said rod and to said lead screw whereby said member is moved longitudinally upon said base.

9. A fence-stay forming machine, comprising a base, a vertically extending gear casing mounted upon said base at one end

thereof, a standard carried by said base adjacent its other end, a member mounted on said base for movement between said casing and said standard, a wire-receiving tube 65 having a bearing adjacent one end in said casing and being provided with wire-engaging means at its other end, a forming tool having wire-engaging means secured to said member and providing a slide-bearing for 70 said tube, a lead screw journaled in said casing and said standard having a slide-bearing in said member, means pivotally carried by said member adapted to releasably engage said lead screw for imparting 75 movement to said member, means held under spring tension for retaining said pivoted means in engagement with said screw, a trip device adapted to contact with and disconnect said pivoted means from engagement 80 with said lead screw, and gear mechanism within said casing for imparting simultaneous rotary movement to said rod and to said lead screw whereby said member is moved longitudinally upon said base. 85

10. A fence-stay forming machine, comprising a base, a vertically extending gear casing mounted upon said base at one end thereof, a standard carried by said base adjacent its other end, a member mounted on 90 said base for movement between said casing and said standard, a wire-receiving tube having a bearing adjacent one end in said casing and being provided with wire-engaging means at its other end, a forming tool 95 having wire-engaging means secured to said member and providing a slide-bearing for said tube, a lead screw journaled in said casing and said standard having a slide-bearing in said member, means pivotally 100 carried by said member adapted to releasably engage said lead screw for imparting movement to said member, means held under spring tension for retaining said pivoted means in engagement with said screw, 105 a trip device adapted to contact with and disconnect said pivoted means from engagement with said lead screw, a spring drum carried by said base, a cable having one of its ends secured to said member and adapted 110 to wind on said drum whereby said member is returned to initial position when said pivoted means is disconnected from said screw, and gear mechanism within said casing for imparting simultaneous rotary movement to said rod and to said lead screw 115 whereby said member is moved longitudinally upon said base.

In testimony whereof, I have signed my name to this specification.

JOSEPH T. TILLMAN.
